(57) **CLAIM**

The ornamental design for a leg support for a table, as shown and described.

DESCRIPTION

FIG. 1 is a perspective view of a leg support for a table, illustrating a leg support that is adjustable in height;

FIG. 2 is a front view of the leg support for a table shown in FIG. 1, with the back view being a mirror image thereof; and,

FIG. 3 is a right side view of the leg support for a table shown in FIG. 1, with the left side being a mirror image thereof.

The broken lines shown in the figures are for illustrative purposes only and form no part of the claimed design.
